Primary Examiner — Selina Sikder*(74) Attorney, Agent, or Firm* — Manabu Kanesaka**CLAIM**

The ornamental design for a remote controller for boiler, as shown and described.

DESCRIPTION

FIG. 1 is a perspective view of a remote controller for boiler showing my new design;
FIG. 2 is a front view thereof;
FIG. 3 is a rear view thereof;
FIG. 4 is a plan view thereof;
FIG. 5 is a bottom view thereof;
FIG. 6 is a left side view thereof;
FIG. 7 is a right side view thereof; and,
FIG. 8 is a cross-sectional view thereof taken along line 8-8 in FIG. 2.
